UNITED STATES PATENT OFFICE.

ARTHUR PRIMROSE YOUNG, OF KENILWORTH, AND AUSTIN THOMAS STACE, OF COVENTRY, ENGLAND, ASSIGNORS TO GENERAL ELECTRIC COMPANY, A CORPORATION OF NEW YORK.

TELEPHONE HEAD SET.

Application filed September 10, 1923, Serial No. 661,757, and in Great Britain October 16, 1922.

Our invention relates to head attachment means for telephone receivers of the kind in which the ear-pieces are held in position over the ears in the reception of wireless or ordinary telegraphy or telephony.

The object of our invention is to provide a construction for telephone head sets which will permit of any desired adjustment of the ear pieces to accommodate different users and 10 in which the ear-piece will be securely held against accidental detachment from the head band and prevented from rotating in such a way that the cords may become twisted.

According to our invention the ear-piece 15 of the telephone receiver is connected to its supporting member through a ball and socket joint and means are provided for limiting the rotation of the ear-piece about its horizontal axis to a predetermined amount. This 20 may be brought about by the provision of studs or shoulders projecting from the ear piece and arranged one on each side of the supporting member and adjacent thereto. It may also be brought about by providing a 25 flat portion on the ball cooperating with a corresponding flat portion in the socket.

In carrying out our invention we may also provide an improved construction of earpiece connecting rod or supporting member by 30 means of which the connecting rod is prevented from rotating about its own axis when the adjusting screw, securing it to the head band gear, is loose.

The novel features which we believe to be 35 characteristic of our invention are set forth with particularity in the appended claims. Our invention itself, however, will best be understood by reference to the following description taken in connection with the accompanying drawing in which Fig. 1 represents one-half of a telephone receiver embodying our invention; Fig. 2 shows the supporting member with the socket portion in section; Fig. 3 is an enlarged view of the ball portion 40 of a modification of this invention; and Fig. 4 is a transverse elevation thereof.

In Fig. 1 the ear piece member 1, which may be of any desired type, has secured to it, or moulded into it, a metal plug 2 having projecting portions 3 arranged adjacent to and on each side of the end of the supporting member 4. This metal plug 2 is provided with an axial recess which is preferably screw-

threaded, and adapted to engage the screw 55 threaded stem 5 of the ball member. A nut 55 is fixed to the stem to assist in screwing the ball member into the metal plug. A convenient way of forming the projecting portions or lugs 3 is to mount a strip of metal between the nut 6 and the metal plug 2, this strip having 60 a bent over point which enters the material of the ear-piece and prevents rotation of the strip when the nut 6 is screwed tight into the recess in the plug. The ends of the strip are then bent up to form the lugs 3. The 65 socket portion of the joint consists of a cup-shaped member 7 rounded at the bottom, as shown at 8, to form a bearing for the ball 9 and provided with a longitudinal recess 10 adapted to receive the stem of the ball member. The upper portion of the socket is screw-threaded internally and adapted to receive the plug 11. In assembling, the ball portion is placed in the socket, the stem of the ball portion passing along the groove 10, and the plug 75 or cap 11 is then screwed into the upper portion of the socket. Connecting rod 4 is inserted into a longitudinal hole provided in the cap 11 and a rivet 12 is then forced in, securing together the plug 11, the end of the 80 connecting rod 4, and the socket portion 10. The rod 4 is preferably offset, as shown at 13, and is preferably of hexagonal cross-section as shown, cooperating with a similarly shaped hole in the stud 14, which is carried by 85 the head band 16. A screw or nut 15 is secured to the free end of the rod 4 so that the rod 4 cannot be withdrawn from the head band 16 when the adjusting screw 17 is loose.

In a modification of our invention shown in 90 Figs. 3 and 4, the ball member 9 is provided with a groove 18 arranged to cooperate with the end 19 of the plug 11 and sufficient space will be left between the two members to allow of limited movement therebetween. In this 95 case, the shoulders 3 of the metal plug 2 would be omitted.

With this construction of telephone receiver, the ear piece member 1 has limited universal movement so that it can easily be adjusted to the ears. The ear piece, however, cannot be rotated on its horizontal axis and thus the conducting leads attached to the terminals of the receiver do not become twisted on this account. To suit the position of the 100 user's ears with respect to the head band gear,

connecting rod 4 can be adjusted in a vertical direction by means of the adjusting screw 17 and during such adjustment it is prevented from rotating about its axis owing to its hexagonal cross section cooperating with the similarly shaped hole in the stud 14 of the head band gear.

Our invention admits of various other arrangements or modifications than those herein described. For instance, the socket portion may be rigidly secured to the ear piece and the ball portion may be carried by the supporting member.

What we claim as new and desire to secure by Letters Patent of the United States, is:—

1. The combination in a telephone head set of a ball and socket joint connection between the ear piece and the support therefor and means for limiting to a predetermined amount the rotation of the ear piece about horizontal axes perpendicular to and parallel with the plane of said ear piece.

2. The combination in a telephone head set of an ear piece having a metal plug secured thereto, a ball having a stem which is secured to said plug, a supporting member having a socket adapted to receive said ball, and means for limiting the rotation of the ear piece about a horizontal axis perpendicular to the plane of the ear piece to a predetermined amount.

3. The combination in a telephone head set of an ear piece having the ball member of a ball and socket joint secured thereto, a supporting member having a socket for said ball formed thereon, and means for limiting the rotation of the ear piece about a horizontal axis perpendicular to the plane of the ear piece to a predetermined amount.

4. The combination in a telephone head set of an ear piece having the ball member of a ball and socket joint secured thereto, a supporting member having a socket for said ball formed thereon and means attached to said ear piece for limiting the rotation of the ear piece about a horizontal axis perpendicular

to the plane of the ear piece to a predetermined amount.

5. The combination in a telephone head set of an ear piece having a metal plug secured thereto, a ball having a stem which is secured to said plug, a supporting member having a socket adapted to receive said ball, said socket being provided on one side thereof with a slot for receiving the ball stem, and means for limiting the rotation of the ear piece about its horizontal axis to a predetermined amount.

6. The combination in a telephone head set of an ear piece having a metal plug secured thereto, a ball having a stem which is secured to said plug, a supporting member having a socket adapted to receive said ball, said socket being provided on one side thereof with a slot for receiving the ball stem and the upper portion thereof being internally screw-threaded to receive the screw-threaded end of a connecting rod which connects the socket with a head band, and means for limiting the rotation of the ear piece about its horizontal axis to a predetermined amount.

7. The combination in a telephone head set of an ear piece having a metal plug secured thereto, a ball having a stem which is secured to said plug, a supporting member having a socket adapted to receive said ball, said socket being provided on one side thereof with a slot for receiving the ball stem and the upper portion thereof being internally screw-threaded to receive the screw-threaded end of a connecting rod which connects the socket with a head band, said connecting rod being of polygonal section, and passing through a similarly shaped hole in a stud secured to the head band whereby it is prevented from rotating, and means for limiting the rotation of the ear piece about its horizontal axis to a predetermined amount.

In witness whereof, we have hereunto set our hands this sixteenth day of August, 1923.

ARTHUR PRIMROSE YOUNG.
AUSTIN THOMAS STACE.
